CLAIM

The ornamental design for a float for swimming pool chlorine dispenser, substantially as shown and described.

DESCRIPTION

FIG. 1 is a left side elevation of a float for swimming pool chlorine dispenser showing my new design, the right side being identical in appearance;

FIG. 2 is a front elevation thereof;

FIG. 3 is a top plan view thereof;

FIG. 4 is a bottom plan view thereof; and

FIG. 5 is a rear elevation thereof.

The right side view is substantially identical to the left side view shown in FIG. 1.

FIG. 1

FIG. 2

FIG. 5

FIG. 4

FIG. 3
